UNITED STATES PATENT OFFICE

2,472,202

TOOL RETAINER

Walter D. Fish, Claremont, N. H., assignor to Joy
Manufacturing Company, a corporation of
Pennsylvania

Application June 1, 1946, Serial No. 673,819

10 Claims. (Cl. 279—19.1)

1

This invention relates to retainers for working tools and more particularly to an improved retainer for the drill steel of a hammer rock drill.

An object of the present invention is to provide an improved tool retainer. Another object is to provide an improved retainer for the drill steel of a hammer rock drill whereby the reciprocable collared drill steel is retained in an improved manner in the drill chuck. A further object is to provide an improved mounting for the retainer yoke of a drill steel retainer. A still further object is to provide an improved resilient pivotal mounting for the retainer yoke. Yet another object is to provide an improved one-piece retainer yoke having side arms formed with integral rearward portions adapted for lateral connection with trunnions integral with the chuck housing. A still further object is to provide an improved tool retainer having a novel arrangement and combination of parts. These and other objects and advantages of the invention will, however, hereinafter more fully appear.

In the accompanying drawing there is shown for purposes of illustration one form which the invention may assume in practice.

In this drawing:

Fig. 1 is a front elevational view of the forward portion of a rock drill with which an illustrative form of the improved tool retainer is associated.

Fig. 2 is a side elevational view of the structure shown in Fig. 1.

Fig. 3 is a view in central longitudinal section taken substantially on lines 3—3 of Fig. 2.

Fig. 4 is a front end view of the structure shown in Figs. 1 and 2.

Fig. 5 is a detail sectional view taken substantially on line 5—5 of Fig. 1.

Fig. 6 is a cross-sectional view taken on lines 6—6 of Fig. 3.

In this illustrative construction, the reference character 1 generally designates a hammer rock drill with which the improved tool retainer, generally designated 2, is associated. The hammer rock drill, of which only the forward portion is shown herein, comprises a front chuck housing 3 providing a retainer support and containing a chuck member 4 for slidably receiving and supporting the shank 5 of a conventional reciprocable drill steel 6. The drill steel has a usual collar 7 which limits rearward movement of the steel shank in the drill chuck; and the improved steel retainer cooperates, as later explained, with the steel collar to prevent unintentional ejection of the steel shank from the chuck during the drilling operation. The pressure fluid hammer motor

of the rock drill includes a motor cylinder 8 to which the chuck housing is suitably secured and which contains a usual reciprocatory hammer piston for percussively actuating the drill steel, in a manner well known to those skilled in the art. The structure of the rock drill may be generally similar to that disclosed in the John C. Curtis application, Serial No. 667,383, filed May 4, 1946, although it will be evident that the tool retainer may be associated with other sorts of drills.

Now referring to the improved tool retainer 2, it will be noted that a retainer yoke 9 has a front yoke or abutment portion 10 which partially encircles the drill steel in advance of the steel collar 7 and has rearwardly extending side arms 11, 11 disposed along opposite sides of the chuck housing. The retainer side arms have, at their rearward portions, enlarged generally C-shaped or hook-shaped pivot portions 12 formed with front bearing recesses 13 and deeper rearwardly disposed recesses 14, the latter recesses receiving and supporting resilient elements preferably rubber buffers 15 and arcuate plates or shoes 16. Projecting laterally from the sides of the chuck housing near its forward end are cylindrical trunnions 17, 17 having angularly related flattened surfaces 18 and 19. The axes of the trunnions are parallel and adjacent to a diametric plane 20 passing through the longitudinal center of the drill. These trunnions project into the bearing recesses of the retainer arms; and the rearwardly facing curved bearing surfaces of the bearing recesses are yieldingly held in contact with the cylindrical surfaces of the trunnions by the rubber buffers which are held under compression in the arm recesses 14 rearwardly of the trunnions. The compressed rubber buffers act on the arcuate shoes 16 to hold the flat surfaces 20 thereof against the flattened surfaces 18 of the trunnions to maintain the retainer yoke in its operative steel retaining position, as shown. Closure plates or side covers 21 are secured, as by welding, to the outer sides of the retainer arms to close the outer sides of the arm recesses 13, 14, as shown, and these side closures serve to maintain the rubber buffers and shoes against outward displacement from the recesses in an obvious manner. Projecting laterally from the retainer yoke centrally near the forward yoke or abutment portion 10 is a curved handle 22 whereby the retainer yoke may be laterally swung on its pivotal mounting into its released position as indicated in dotted lines in Fig. 2. When the retainer is released, the flat surfaces 20 on the

arcuate shoes 16 engage the flattened surfaces 19 on the trunnions to maintain the retainer yoke in its released position. When the retainer yoke is in the dotted line position shown, the steel shank may be withdrawn axially from the drill chuck. The recessed, generally hook-shaped rearward portions of the yoke side arms have open slots or side openings 23 extending between the bearing recesses and the side edges of the arms by means of which the yoke arms may be readily laterally connected to their bearing mountings on the trunnions. When it is desired to release the retainer yoke from the trunnions, the rubber buffers may be compressed sufficiently to release the bearing recesses from the trunnions so that the retainer arms may be moved laterally from the trunnions with the latter passing through the side openings 23. As the mode of use of the improved tool retainer will be clearly apparent from the description thereof, further description is considered unnecessary. Other uses and advantages of the improved tool retainer will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a support having lateral trunnions, a swingable tool retainer pivotally mounted on said trunnions and having side arms formed with generally hook-shaped rearward portions provided with front bearing recesses for receiving said trunnions and rearwardly extending deeper recesses, there being side openings extending laterally from the bearing recesses out through the sides of the arms to permit lateral connection of the retainer arms with said trunnions, said bearing recesses having front walls providing rearwardly facing curved bearing surfaces, yieldable buffers carried by said retainer and arranged in said rearwardly extending recesses rearwardly of said trunnions, and shoes arranged in said rearwardly extending recesses and engaged by said buffers and yieldingly pressed by said buffers into contact with the rear sides of said trunnions to hold the curved bearing surfaces of said bearing recesses rearwardly in pivotal contact with the front sides of said trunnions.

2. In combination, a support having lateral trunnions formed with relatively inclined flattened surfaces, a swingable tool retainer pivotally mounted on said trunnions and having side arms formed with generally hook-shaped rearward portions provided with front bearing recesses for receiving said trunnions and rearwardly extending deeper recesses, there being side openings extending laterally from said bearing recesses out through the sides of the rearward portions of said arms to permit lateral connection of the retainer arms with said trunnions, said bearing recesses having front walls providing rearwardly facing curved bearing surfaces, yieldable buffers carried by said retainer and arranged in said rearwardly extending recesses rearwardly of said trunnions, and plates arranged in said rearwardly extending recesses and engaged by said buffers and yieldingly pressed by said buffers into contact with the rear sides of said trunnions to hold

the curved surfaces of the bearing recesses rearwardly in pivotal contact with the front sides of said trunnions, said plates engaging said flattened surfaces in different positions of said retainer to hold the latter in either its operative tool retaining position or its inoperative released position.

3. In combination, a support having lateral trunnions, a swingable tool retainer pivotally mounted on said trunnions, and having side arms formed with integral enlarged rearward portions adapted for lateral connection with said trunnions, said integral rearward portions provided with recesses for laterally receiving said trunnions, said recesses being closed at their outer sides and having curved front walls providing rearwardly facing bearing surfaces, yieldable buffers carried by said rearward portions of said retainer and arranged in said recesses rearwardly of said trunnions, and plates arranged in said recesses between said buffers and said trunnions and yieldingly pressed by said buffers into contact with the rear sides of said trunnions, said buffers urging said retainer rearwardly relative to said trunnions to hold said bearing surfaces in pivotal contact with the front surfaces of said trunnions.

4. In combination, a support having lateral trunnions near its forward end and adapted to receive the shank of a reciprocable collared tool, a swingable one-piece retainer yoke having side arms adapted for lateral connection with said trunnions and at their rearward portions pivotally mounted on said trunnions, and yieldable means carried by said rearward portions of the side arms of said yoke for urging said side arms rearwardly into pivotal contact with said trunnions, said arms having recesses extending rearwardly of said trunnions to receive said yieldable means and laterally receiving said trunnions, said recesses having curved front walls providing rearwardly facing bearing surfaces engaging the front surfaces of said trunnions.

5. In combination, a support having a transverse integral trunnion, a swingable one-piece retaining member having a front abutment with which the collar of a reciprocable tool is engageable, and having a side arm provided with an integral rear portion adapted for lateral attachment to said trunnion and pivotally engaging at its rear portion said trunnion, and resilient means carried by the rear portion of said arm rearwardly of said trunnion for yieldingly urging said retaining member rearwardly into pivotal contact with the front side of said trunnion.

6. In combination, a support having lateral trunnions, a swingable tool retainer yoke having integral side arms formed with generally C-shaped rearward portions with the open side of each C of sufficient width to permit lateral connection of said side arms with said trunnions, said C-portions having their inner walls providing recesses with the forward walls of the recesses providing rearwardly facing curved bearing surfaces pivotally engaging the forward surfaces of said trunnions and the rearward portions of the recesses extending rearwardly of said trunnions, and yieldable buffers received in said rearward portions of said recesses and acting on the rear sides of said trunnions for yieldingly urging said side arms rearwardly to maintain said bearing surfaces in pivotal contact with the forward trunnion surfaces.

7. A working implement retainer for percussive tools comprising lateral trunnions rigidly secured

to the sides of the tool chuck housing close to the front end of the housing, said housing adapted to receive and support the shank of a collared working implement, a swingable retainer yoke pivotally mounted on said trunnions and having side arms disposed at opposite sides of the chuck housing, said side arms having integral rearward portions adapted for lateral connection with said trunnions and said side arms supporting a yoke portion in advance of said housing and with which the collar of the working implement is engageable, and yieldable buffer means carried by said integral rearward portions of said yoke-side arms for urging said yoke rearwardly with respect to said trunnions into pivotal contact with the latter.

8. A working implement retainer for percussive tools comprising lateral trunnions rigidly secured to the sides of the tool chuck housing close to the front end of the housing, said housing adapted to receive and support the shank of a collared working implement, a swingable retainer yoke pivotally mounted on said trunnions and having side arms disposed at opposite sides of the chuck housing, said side arms having integral rearward portions adapted for lateral connection with said trunnions and said side arms supporting a yoke portion in advance of said housing and with which the collar of the working implement is engageable, and yieldable buffer means carried by said integral rearward portions of said yoke-side arms for urging said yoke rearwardly with respect to said trunnions into pivotal contact with the latter, said side arms having elongated recesses therein extending longitudinally thereof for receiving said trunnions and said yieldable buffer means with the latter located in said recesses rearwardly of said trunnions and acting on the rear surfaces of said trunnions for urging said yoke rearwardly with respect to said trunnions.

9. In combination, a support having lateral trunnions, a swingable tool retainer pivotally mounted on said trunnions and having side arms provided with integral enlarged rear pivot portions adapted for lateral connection with said trunnions and having elongated recesses for receiving said trunnions, said recesses having

curved front walls providing rearwardly facing bearing surfaces pivotally engaging the front surfaces of said trunnions, yieldable buffers carried by said integral rearward portions of said retainer and arranged in said recesses rearwardly of said trunnions, and shoes guided in said recesses and engaged by said buffers and yieldably pressed by said buffers into contact with the rear surfaces of said trunnions to maintain said curved bearing surfaces in pivotal contact with said trunnions.

10. In combination, a support having lateral trunnions provided with relatively inclined plane surfaces, a swingable tool retainer pivotally mounted on said trunnions and having side arms provided with enlarged rear pivot portions having elongated recesses for receiving said trunnions, said recesses having curved front walls providing rearwardly facing bearing surfaces pivotally engaging the front surfaces of said trunnions, yieldable buffers carried by said retainer and arranged in said recesses rearwardly of said trunnions, and shoes guided in said recesses and engaged by said buffers and yieldably pressed by said buffers into contact with the rear surfaces of said trunnions to maintain said curved bearing surfaces in pivotal contact with said trunnions, said shoes selectively engaging said plane trunnion-surfaces in the different angular positions of said retainer with respect to said trunnions to hold said retainer either in its operative retaining position or its inoperative released position.
